DESIGN FOR A COMBINATION SIGNAL AND MIRROR

Elmer F. Oetinger, Buffalo, N. Y.

Application November 9, 1939, Serial No. 88,152

Term of patent 7 years

To all whom it may concern:

Be it known that I, Elmer F. Oetinger, a citizen of the United States, residing at Buffalo, in the county of Erie and State of New York, have invented a new, original, and ornamental Design for a Combination Signal and Mirror, of which the following is a specification, reference being had to the accompanying drawing forming a part thereof.

Figure 1 is a front elevation of the combination signal and rear view mirror embodying my design. Figure 2 is a rear elevation thereof. Figure 3 is a top plan view of the same. Figure 4 is a front end view thereof.

I claim:

The ornamental design for a combination signal and mirror, substantially as shown.

ELMER F. OETINGER.
